DESIGN FOR AN ILLUMINATED ASH TRAY

Kenneth I. Schouten, North Hollywood, Calif.

Application November 5, 1945, Serial No. 123,480

Term of patent 14 years

(Cl. D85—2)

To all whom it may concern:

Be it known that I, Kenneth I. Schouten, a citizen of the United States, residing in the city of North Hollywood, in the county of Los Angeles and State of California, have invented a new, original, and ornamental Design for an Illuminated Ash Tray, of which the following is a specification, reference being had to the accompanying drawing, forming part thereof.

Fig. 1 is a perspective view of an illuminated ash tray for cigars, cigarettes or the like, showing my new design.

Fig. 2 is a top plan view on a reduced scale of the ash tray of Fig. 1.

Fig. 3 is a side view in elevation of the ash tray of the other figures, the scale being the same as that of Fig. 2.

I claim:

The ornamental design for an illuminated ash tray, substantially as shown.

KENNETH I. SCHOUTEN.
